UNITED STATES PATENT OFFICE.

GEORGE WILLIAM BELDAM, OF EALING, ENGLAND.

ENGINE OR MACHINE PACKING.

1,248,997.

Specification of Letters Patent.

Patented Dec. 4, 1917.

Application filed August 20, 1915. Serial No. 46,572.

To all whom it may concern:

Be it known that I, GEORGE WILLIAM BELDAM, a subject of the King of England, residing at Ealing, in the county of Middlesex, England, have invented certain new and useful Improvements in or Connected with Engine or Machine Packings, of which the following is a specification.

This invention has reference to engine or machine packings for making fluid tight joints with or between the working parts of engines or machines, wherein a fluid—steam, air, gases, water and the like—operates the engine or machine, or the fluid is operated upon by it, and for other similar purposes where a fluid tight joint has to be made; and it relates more particularly to that class of such packing which is flexible, and is made up of or comprises laminæ of canvas, asbestos or the like, with or without wires or other metal strands or woven wire or plaited metal or the like, and the laminæ are formed by rolling or coiling or folding a sheet or sheets of fabric up, the packing as a whole being as stated flexible.

The chief object of the present invention is to provide an improved packing of this kind, which while it is at least as effective as rolled up packings of canvas or textile fabric as ordinarily made, it is less expensive.

In the packing hereinafter described and illustrated in the accompanying drawings, the improvements under this invention are comprised; the novel characteristics claimed in respect of it being specified or set out in the claiming clauses concluding the specification.

The packing comprises two portions of different characters as hereinafter explained, namely one part consisting of convolutions of rolled up canvas, woven asbestos fabric, or other woven fabric, which, for example, say is one third of the thickness of the radius of the packing; and may or may not come next the rod, and is subjected to wear; and the other part of the packing is rolled or coiled up or folded with the first mentioned part, and is formed of the same, or equivalent material, but is constituted all of scrap cuttings or residue of the material

from which the first mentioned portion of the packing referred to is made and treated and made up as hereinafter described, and this second mentioned portion may have 55 mixed with it other suitable and less expensive material (as at present packings very often have) according to the nature of the packing, and according to whether it is required for steam, water, air or other fluid. 60

These scrap cuttings are disintegrated or reduced by suitable machinery, and worked up or mixed together so as to form a homogeneous mass, which is rolled out into a thin sheet form. In the packing, this inner material may present the same appearance as the outer portion.

In the drawing,

Figure 1 is a perspective view of my improved packing.

Fig. 2 is a similar view of a modified form of packing.

Fig. 3 is a detail perspective section of the packing, having a cellular core.

Fig. 4 illustrates a perspective partial section of a built up packing having the characteristics of my invention.

Fig. 5 is a view similar to Fig. 4, but illustrating a different form of built up packing.

Fig. 6 is a view similar to Fig. 4, but illustrating a still further development of a built up packing.

Fig. 7 is a perspective partial section of a built up packing having rivets on one face.

Fig. 8 is a detail perspective view of one of the slabs or plates employed in making the packing bars.

In the packing as illustrated in Fig. 1 of the drawings, *a* represents the rolled up canvas, woven asbestos cloth, or other woven fabric on the outside of the packing; and *b* represents the material made of the rolled up sheet formed from the disintegrated scrap cuttings.

A modification of the packing just described, is shown in Fig. 2, in which the center portion consists of alternate laminæ of canvas or like cloth, and the composition sheeting described, and this combined coiled up portion, forms the core in the center of the packing.

In some cases in the center of the packing a cellular core is provided, so that it (the core) is elastic, and the cells containing air; and the cells may be formed by employing 5 small pieces of rubber or other suitable material, spaced at certain distances apart. The core thus constitutes a pneumatic cellular one.

This packing is illustrated in Fig. 3, in 10 which *c* represents the small pieces of rubber or like material, and *d* the air cells, or spaces between them.

As a modified manner of providing this 15 cellular core there may be used in the center of the packing, rubber sponge or like material containing air in cells, which will act pneumatically, as in the former case.

In building or making up this packing, the different parts specified can be made 20 of different degrees of resilient material; namely the outside—that is the part which comes next the rod or the wearing part—may be made relatively soft and pliable, while the inner part may be relatively hard. Or, 25 the outside of the packing which comes next the rod can be of the harder material, similarly as in packing known as "semi-metallic", as for instance similarly as that described and shown in the specification of my 30 British Patent No. 11562 of 1913; while the part within it may be of a softer or more resilient nature. Also in some cases the back part may be made of composition consisting 35 of scrap cuttings or residue of the material from which the packing is made, either alone, or mixed with other suitable less expensive or inexpensive material. And this back part instead of being in laminæ of sheeting or cloth, may be made of the said 40 composition or material compounded together and made into a more or less homogeneous solid mass.

Packing of this character is illustrated in Figs. 4 to 6 of the drawings.

45 Fig. 4 shows the packing in which the outside portion which comes next to the rod is of the harder material consisting of composition *b*, made up and compressed in a homogeneous mass with a suitable adhesive, such as is used in making packings of this 50 kind; this portion being similarly arranged in the packing, as the hard portion of the packing as shown in the specification of my British Patent No. 11562 of 1913; while the 55 softer or more resilient portion *a*, which forms the back part, may be made of canvas sheets folded up together as indicated by the drawing, or this sheeting may if desired be made of the scrap cutting or waste 60 composition specified.

The portion *b* is generally of the form of the hard portion of the said semi-metallic packing described and shown in my British Patent No. 23820 of 1913; namely it is provided 65 with gaps *e* at suitable intervals—say

deep V recesses; and there are two thick bands or bars of this composition material forming the face and center portion of the packing; and these recesses in the different bars or bands are arranged in "break joint" 70 disposition, so that a gap in one bar lies under or over a solid portion of the other bar.

In Fig. 5 the harder portion *b* of the packing made of the composition in strips, as shown, having between them laminæ or 75 strips *f* of canvas or woven asbestos fabric; and in this case also—which is of the general form of packing shown in Fig. 4—the back and outer portion *a* may be of folded sheets made of the composition, or of canvas or asbestos woven fabric.

In Fig. 6 the back and outer portion *a*, in which the wearing or face part of the packing lies, is made of the composition or material made into a more or less homogeneous 85 mass, compacted and pressed to the required degree; and this part of this material is marked *b*¹, and is inclosed with a wrapping of canvas or of other material, and is provided with bars *b* as in Fig. 4. 90

In Fig. 7 there is shown a packing of the character herein referred to, provided with metal rivets or studs. In this packing the part *b* is made up of composition above described, and the rivets or studs *i* are fitted in it; the rivets or studs being made of any suitable metal used in packings of the kind concerned. The rivets or studs may be of bifurcated form such as are used in tire treads, or of other suitable kind, and secured by washers at their bases or in any suitable manner; and they are preferably set more or less closely together in rows, as indicated.

The back and outer portion of the packing in this case, may be made of the convolutions or laminæ of canvas; or woven asbestos cloth; or it may consist of the composition such as described with reference to Fig. 7.

In Figs. 4 and 5, the packing is shown 110 practically of rectangular form, but it may be of other shapes, according to requirements.

Concerning the manner of treating, the 115 cuttings or residue of the material, from which the canvas, asbestos, (with or without wire woven) packings are made, this residue or cutting is taken and reduced or disintegrated, say in a grinding or mixing mill, and mixed up together in a homogeneous 120 mass, and thoroughly treated; and in some cases graphite or like lubricant may be mixed with it; and where the material so mixed is of too "dry" a nature, such as when it comprises asbestos and wire woven waste 125 cuttings an extra small amount of suitable rubber compound is mixed, or another known adhesive suitable to the purposes with it. Sometimes other waste cuttings, such as the waste cuttings, clippings, et 130

cetera, from the manufacture of pneumatic tires, in which canvas has been used, and which is unvulcanized, can be mixed with the waste from the manufacture of packings, 5 and therefore is unvulcanized, which is similarly reduced or disintegrated and treated as described.

This mass of mixed material is then 10 passed through heated calender rollers, and rolled out under pressure into a thin layer, in some cases as thin as the canvas or asbestos cloth or material with which it is to be incorporated in the manufacture of the packing, where so incorporated.

15 In the case where the packing is made into bars, as it were, as shown in Figs. 5 to 7, this form of the material would be made by passing the mass between rollers to a wider gage, say half an inch, five-eighths, or 20 three quarters of an inch thick, according to the size of the packing for which it is required. Or it may be made up in a frame of the size required, and in the thickness required, and introduced between the plates, 25 and compressed between them, under a pressure which would give the material the required density; and one of these plates may have V or other suitable shaped projections or ribs on it, so that when the plates are 30 pressed together by hydraulic or other pressure, there is produced in the slab the V or like shaped grooves. A section of this slab is shown in Fig. 8.

The bars *b* are made from the slab by cutting it transversely to the direction of the grooves *e*; the width of the bars being so cut off, being that required. The thickness or depth will be that of the slab, which will be regulated according to the size of the 40 packing.

I am aware that packings have been made in which a backing has been employed, and that the backing may be of a different fabric and structure from the other part, and I 45 make no general claim to a packing having this characteristic.

While in the above description it has been inferred or stated in general that the packing is to be used in connection with engines 50 or machines in which the parts to be packed have relative movement, yet it may be employed between parts of engines or machines or apparatus in which the adjacent surfaces or parts, between which it is desired to make 55 a steam or fluid tight joint, are stationary.

What is claimed is:—

1. A packing of the flexible type for engines and machines comprising two laminated portions of material of different structural characteristics, one of such portions consisting of woven material and the other of such portions being made up from disintegrated woven material; substantially as described.

65 2. A flexible packing for engines and ma-

chines comprising two portions having different structural characteristics, one portion being formed of the equivalent material as the other portion and consisting of the scrap 70 clippings and waste of the material constituting the other portion, the said clippings and waste being disintegrated and the disintegrated material being mixed with an adhesive and pressed into the required form; substantially as described.

3. A flexible packing for engines and machines comprising two portions having different structural characteristics, one portion being formed of the equivalent material as the other portion and consisting of the scrap 80 clippings and waste of the material constituting the other portion, the said clippings and waste being disintegrated and the disintegrated material being mixed with rubber adhesive and rolled into sheet form; sub- 85 substantially as described.

4. A flexible packing for engines and machines comprising layers of two different woven materials of different structural characteristics and having a pneumatic chambered core at the inner part; substantially as 90 described.

5. A flexible packing for engines and machines comprising layers of two different woven materials of different structural characteristics and having a pneumatic cellular core at the inner part; substantially as 95 described.

6. A packing of the flexible type for engines and machines comprising portions of 100 woven materials having different structural characteristics one of such portions being relatively hard and another of such portions being relatively soft, the relatively soft portion consisting of woven textile material 105 arranged in layers over the surfaces of the harder material which consists of disintegrated woven material mixed with an adhesive and compressed into blocks; substantially as described.

7. A packing of the flexible type for engines and machines comprising portions of woven materials having different structural characteristics one of such portions being relatively hard and another of such portions being relatively soft, the relatively soft portion consisting of woven material arranged in layers over the surfaces of the harder material which consists of disintegrated woven asbestos mixed with an adhesive 115 and compressed into blocks with metal rivets combined therewith; substantially as described.

8. A flexible packing for engines and machines comprising alternate layers of woven 125 textile, asbestos or like material, and disintegrated woven textile, asbestos or like material, in sheet form; substantially as described.

9. A flexible packing for engines and ma- 130

chines comprising two layers of different structural characteristics, one of which is the face part which comes next the working surface and is made of harder material than that of the other part and consists of woven material disintegrated and compressed into shape; substantially as described.

In testimony whereof I have signed my name to this specification in the presence of two subscribing witnesses.

GEORGE WILLIAM BELDAM.
